UNITED STATES PATENT OFFICE.

JOHN J. PLEGER, OF CHICAGO, ILLINOIS.

BOOK-BACK-GLUING MACHINE.

Application filed April 5, 1927. Serial No. 181,053.

This invention relates to improvements in devices for applying adhesive to the backs of books or pamphlets in preparation for the reception of a paper cover or for rounding and backing when books are bound with a stiff or board cover.

The principal object of the invention is to provide a machine which will apply the adhesive to the books or pamphlets rapidly and uniformly.

The invention further relates to certain novel mechanical features and structural details hereinafter set forth and illustrated in the attached drawings, in which:

Figure 1 is a plan view of a machine made in accordance with my invention;

Fig. 2 is a side elevation of the machine;

Fig. 3 is an end elevation of the machine;

Fig. 4 is a section on the line 4—4, Fig. 3;

Fig. 5 is a section on the line 5—5, Fig. 1;

Fig. 6 is a section on the line 6—6, Fig. 5;

Fig. 7 is a section on the line 7—7, Fig. 5, and

Fig. 8 is a fragmentary sectional view illustrating a modification.

Referring to the drawings, the machine comprises a suitable framework consisting of a pair of side pieces 1 and 2 joined together by suitable cross bars 3, 4, 5, 6, 7, 8, 9 and 10.

Supported on brackets 11 at the top of the frame are a pair of longitudinal rails or tracks 12 in the form of channels, these rails extending the entire length of the frame and at one end supporting a table 13. The rails 12 constitute tracks for a carriage 14. The carriage 14 consists, as best shown in Fig. 1, of a more or less open frame having at one side two supporting wheels 15 which operate in one of the rails and comprising a transverse arm 16 extending across the frame and carrying a single wheel or roller 17 which operates in the rail at the opposite side of the frame.

The forward end of the carriage is connected through a rod 18 with a crank arm 19 on a jack shaft 20, which shaft is journaled in a bearing 21 at one end of an arm 22 the other end of which is secured to a vertical shaft 23 at the table end of the frame, all as well shown in Figs. 1 and 4. The arm 22 carries a freely rotatable gear 24 on its under side which meshes with a stationary gear 25 secured by bolts 26 to the cross bar 3 of the frame, the gear 25 being concentric with the shaft 23 which extends through an opening in the gear. The gear 24 also meshes

with a gear 27 on the vertical shaft 20 journaled as previously described in the outer end of the arm 22. When under these conditions the shaft 23 is rotated from a source 60 hereinafter described, the resulting movement of the arm 22 results through the medium of the fixed gear 25 and the pinion 24 in an independent rotation of the shaft 20, and the direction of rotation of the latter shaft is 65 opposite to the direction of rotation of the shaft 23, so that as the arm 22 swings clockwise from the position shown in Fig. 1, the arm 19 will be swung in the opposite direction and will lie directly over the arm 22 70 when the latter has advanced in its angular movement through an angle of 90°. Continued angular movement through a further angle of 90° again brings the arms 22 and 19 75 into the extended position, as shown in Fig. 1, but in a diametrically opposite direction. It will be apparent that this gives the same effect, so far as the travel of the carriage 14 is concerned, as though a single crank arm equal in length to the joint length of the arms 22 and 19 were used on the shaft 23 instead

of the arrangement described, but by the latter device the space covered by the arms when extending transversely of the frame is cut in half, and the arm 19 does not project beyond the side of the frame at any part of the movement.

The shaft 23 carries at its lower end a bevel gear 28 which meshes with a bevel gear 29 on a transverse shaft 30, and this latter 90 shaft carries a gear 31 which is operatively connected through the medium of a pinion 33 and suitable reduction gearing enclosed in a housing 34 with an electric motor 35 which constitutes the prime mover of the machine. 95

As shown in Fig. 3, the gear 29 turns loosely on the shaft 30 and is adapted to be operatively connected with the shaft through a clutch 36. The clutch 36 is operated through a lever 37 pivoted at 38 to the frame, and 100 this lever is operatively associated with a treadle 39 pivoted to the frame at 40. The treadle is normally held in an elevated position through the medium of a spring 41 and a link 42, and the arrangement is such 1 that when the treadle is depressed, the clutch member 36 is oscillated in such manner as to engage the clutch and thereby effect an operative connection between the shaft 30 and the gear 29. The upper end of the lever 37 110 carries on a vertical pin a roller 43, and this roller is adapted to be engaged by an arm

- 44 on the shaft 23 as the latter rotates, in such manner as to disengage the clutch 36 which previously has been engaged, as described, by means of the treadle. The arrangement is such that following the initial engagement of the clutch 36 by pressure of the treadle 39, the clutch will remain in engagement of its own accord during one complete rotation of the shaft 23, after which 10 the arm 44 engages the roller 43 and shifts the lever 37 to disengage the clutch. In each instance, the mechanism is so timed that the clutch is disengaged when the carriage 14 occupies the rear end of its travel, as shown 15 in Fig. 1, and from this position a complete rotation of the shaft 23, occurring when the treadle 39 is depressed, will move the carriage through one complete reciprocation in the frame.
- 20 Pivotaly mounted in the frame below the rails 12 is a frame 45, this frame being pivoted at one side on a pin 46 in the frame and at the opposite side on a pin 47 on an arm 48 projecting inwardly from the side piece 1 of the frame. The frame 45 carries a rotary gluing roll 49 and is supported by one of a pair of arms 50—51 which are carried by a rock shaft 52 journaled in arms 53 depending from the frame and which, as shown in Fig. 3, 25 project inwardly and carry at their inner ends in each instance an arm 54 having a roller 55 at the top, which in the case of the arm 51 engages the under side of a projecting arm 56 on the frame 45.
- 30 The shaft 52 has extending upwardly therefrom an arm 57 which carries at the top a roller 58 which normally occupies a position in the path of a cam bar 59 at one side of the carriage 14 whereby as the carriage is moved 35 forwardly, as described above, the cam 59 engaging the roller 58 shifts the upper end of the arm 57 outwardly, thereby rocking the shaft 52 and through the arm 50 elevating the frame 45 with its gluing roll 49 around the pivots 46—47. The cam bar 59, as shown in 40 Figs. 1 and 3, is carried by arms 60 projecting transversely from the carriage 14 and over the outer side of the rail 12.
- 45 The arm 51, as shown in Fig. 3, extends inwardly and through the extension 54 and roller 55 thereof engages the under side of a lever arm 61 on a transverse shaft 62 suitably journaled in the frame, and this shaft carries arms 63, 63 which at their outer ends support 50 in a position adjacent the rear side of the roller 49 a frame 64 in which is supported a pair of transverse brushes 65. It will be apparent that the rocking of the shaft 52 as described through the medium of the cam 59 on the carriage results in the elevation of these brushes 65 in substantially the same manner and at the same time as the elevation 55 of the adhesive roll 49.
- 60 The roll 49, which is mounted on a shaft 66 journaled in open bearings 67 in the frame 45, 65
- is normally rotated from the motor 35 through transmission consisting of a gear 68 on the roll shaft 66, an intermeshing gear 69 on a jack shaft 70 journaled in the frame, a gear 71 at the outer end of the shaft 70, a pinion 72 70 meshing with the gear 71 and carried by a second jack shaft 73, a sprocket 74 at the outer end of the shaft 73, a drive chain 75 which connects the sprocket 74 with a sprocket 76 on the shaft 30, and the gearing previously 75 described which connects this shaft 30 with the motor.
- 70 Means is provided, however, for accelerating the rotative velocity of the roll 49 during the period that the roll is elevated, as previously set forth. It will be noted by reference to Fig. 1 that the shafts 70 and 73 carry intermeshing gears 77 and 78 respectively. The gear 78 is fixed to the shaft 73, while the gear 77, as shown in Fig. 5, is loosely 80 mounted upon a sleeve 79, which in turn journals on a collar 80 keyed to the shaft 70. Also as shown in Fig. 5, the gear 71 is secured through the medium of a feather 81 to the said sleeve 79, and is normally operatively 85 connected with the shaft 70 through a ratchet clutch consisting, as shown in Fig. 7, of a series of rollers 82 seated in beveled recesses in the periphery of the collar 80 and adapted to fix the sleeve 79 with the said collar in one 90 rotative direction only. In other words, as the sleeve or bushing 79 moves in the direction indicated by the arrow in Fig. 7, the rollers 82 are wedged into the narrow ends of the 95 recesses 83 which they occupy and thereby 100 frictionally secure the bushing 79 and the collar 80 together so that the collar is rotated with the said bushing.
- 105 As previously stated, the gear 77 is loosely mounted on the bushing 79 but is adapted to be connected with the shaft 70 through the medium of a clutch consisting of a collar 84 splined to the shaft 70 and carrying a projecting pin 85 which when the collar 84 is advanced against the tension of a spring 86 in a manner hereinafter set forth engages one of a series of pins 87 carried and projecting from one face of the gear 77, as shown in Fig. 5. As shown, the pin 85 is slidable in the collar 84 and is normally held in an advanced projecting position by a spring 88 shown in Figs. 5 and 6, which permits the pin to move rearwardly in the event of the end of the pin meeting the outer end of the pin 87 on the gear 77. The effect of the engagement of the pins 85—87 is to fix the gear 77 with respect to the shaft 70 whereby the gear 78 becomes effective to rotate the shaft 70 in the same direction as it is normally rotated through the pinion 72 but at a higher rate of speed, and this is permitted by the ratchet clutch 82—83 previously described. The operation will be clear by reference to Fig. 7, where it will be noted that if the bushing 79 is rotating in the direction of the arrow and carrying with it 110
- 115
- 120
- 125
- 130

through the rollers 82 the collar 80 as previously described, there is nothing to prevent an acceleration of the rotation of the shaft 70 and collar 80 in the same direction, by reason 5 of the fact that the rollers 82 are inoperative to prevent relative angular movement between the bushing 79 and the sleeve 80, except in opposite directions.

The collar 84 is advanced and retracted 10 to the clutch-engaging and disengaging positions through the medium of the arm 57 which as shown in Fig. 6 is in the form of an open yoke embracing and pivotally engaged with the collar 84 through set screws 15 89. As previously described, the arm 57 is moved outwardly when the carriage 14 is advanced through the cam 59 on the carriage which engages the roller 58 at the top of the arm. The outward movement of the arm 57, 20 therefore, results not only in elevation of the adhesive roller 49 and the brushes 65, 65, but also results in an acceleration in the rotative speed of the roller 49 as described above.

It is desirable, as will be made clear hereinafter, that the adhesive roll 49 be elevated and accelerated only when the carriage 14 is moving forwardly from the position shown in Fig. 1. In order to prevent the elevation and acceleration of the roller during the return movement of the carriage, I mount the cam-engaging roller 58, as shown in Fig. 1, upon an arm 96 pivoted at 97 at the top of the arm 57 and adapted to swing to a horizontal position away from the abutting portion 98 of the arm 57. The arm 96 is resiliently held against the abutment 98 by a spring 99. It will be apparent under these conditions that when the carriage 14 is advanced from the position shown in Fig. 1, the resulting engagement of the roller 58 with the cam 59 results in an oscillation of the arm 57 as described. When on the return movement of the carriage 14 the roller 58 is engaged by the cam 59, the direction of the applied forces is such that the arm 96 is swung on its pivot 97 away from the abutment 98 and against the tension of the spring 99, with the result that the arm 57 remains in its normal advanced position which is controlled, as shown in Fig. 5, by the abutment of the collar 84 against the frame piece 1, and the gluing roll 49 remains in the normal depressed position and rotates at the normal speed.

It will be noted that the bracket 45 carries 55 a relatively small solid roller 90 which is adjustable through its supporting sleeves 91, 91 relative to the face of the roll 49, and this roll 90 is normally in contact with the surface of the roll 49 to properly distribute the adhesive which is picked up on the surface of the roll from an adhesive container 91^a immediately under the roll position. This container 91^a which includes a heating element 92 is carried by a support 93 on the upper end 60 of a threaded shaft or screw 94 which is

threaded in a vertical position in the frame cross piece 10, as best shown in Fig. 4. At the bottom of the shaft 94 is a hand wheel 95 by means of which the shaft may be rotated to adjust the vertical position of the adhesive container. It will be noted that the cross pieces 8 with the cross pieces 9 act as guides and braces for the adhesive container 91^a in its various adjusted positions. It will also be noted that the cross-bar 6 carries a second electric or other heating element 103. See Fig. 4, for heating the adhesive in separate receptacles.

It will be noted by reference to Figs. 1 and 4 that immediately below the initial position of the carriage 14, in which it is shown in Fig. 1, there is located a table 100, this table being supported on the cross bar 7. In operation, the books are placed on this table with their backs or bound edges down and are forced by the operator into the angle between the main body of the carriage 14 and the projecting arm 16, as indicated in broken lines in Fig. 1. The inner edges of the main part of the carriages are provided with a vertical flange 101, and the inner edge of the arm 16 is provided with a similar upstanding flange 102, and these flanges in meeting form an angle of 90°. It is against these flanges and into the corner where they meet that the books are firmly pressed with their bound edges resting on the table 100, and the flange 101 is provided with a slot 104 for the reception of a board to build up the height of the flange for large books. Pressure is now applied by the operator or through any desired means to clamp the books against the flanges 101 and 102 so that as the carriage advances, as hereinbefore described, the books move therewith and are held in position against the flanges 102 after the carriage advanced to such a distance that the support of the table 100 is removed.

In practice, therefore, after the operator has adjusted the desired number of books against the flanges 101 and 102 and on the table 100 as described, he depresses the treadle 39, which initiates the movement of the carriage towards the gluing roll 49. As described, the books are held firmly in the adjusted position against the flanges 101 and 102 by the hand of the operator or by any other means that may be desired. It will be noted that the inner face of the arm 16 against which the books bear is inclined to the line of movement of the carriage. As the carriage advances, the gluing roll 49 is elevated to such an extent that it moves into the path and contacts with the bound edges of the books which are carried over the roller and receive therefrom a coating of the adhesive. Simultaneously with the elevation of the roll 49, its acceleration is increased, also as previously described, whereby the glue is evenly distributed over and rubbed into the backs and be-

tween the sections of the books. The backs of the books are then carried over the relatively fixed brushes 65 which remove excess adhesive. After the books have passed over the brushes 65, the operator removes them from the carriage and places them upon the table 13 or at any other point of vantage, after which the covers are applied, or the books separated and left to dry for the next operation, when books are bound with a stiff cover.

The next operation is usually rounding and backing. The carriage continues its travel in the reverse direction until it again occupies the position shown in Fig. 1, at which point the arm 44 on the shaft 23 engages the roller 43 on the arm 37, which results in a disengagement of the clutch 36 and an interruption in the rotational movement of the carriage actuating shaft 23.

It should be noted that due to the angularity of the books with respect to the axis of the brush, the exposed edges of the books are swept clean of adhesive, while the edges of the books against the carriage are protected from excess adhesive by the lower edge of the surfaces against which the books bear. In some instances, rubber aprons 105, see Fig. 8, are used at the bottom of the flanges abutting the books, these aprons registering at their lower edges with the plane of the book backs and by lying snugly against the sides of the books confining the adhesive to the backs of the books only. The adhesive in the receptacle is kept agitated by the continuous rotation of the brush, but the speed of said rotation is so slow as to avoid frothing the adhesive. In operative position, however, the speed of the brush is increased to the desired extent.

I claim:

1. In a book back gluing machine, the combination with a reciprocatory carriage for the books, of a rotary adhesive applicator element positioned adjacent the path of said carriage, mechanism for rotating the applicator, means movable with the carriage for actuating said rotating mechanism, and means for rendering said actuating means effective in one directional movement of the carriage only.

2. In a book back gluing machine, the combination with a reciprocatory carriage for the books, of a rotary adhesive applicator element mounted adjacent the path of said carriage, mechanism for rotating the applicator, and means on said carriage for actuating the said mechanism.

3. In a book back gluing machine, the combination with a reciprocatory carriage for the books, of a rotary adhesive applicator mounted adjacent the path of the carriage, mechanism for rotating the applicator, a clutch controlling the operative connection between the applicator and the said mechanism, and means on said carriage for actuating the clutch.

4. In a book back gluing machine, the com-

bination with a movable carriage for the books, of a rotary adhesive applicator element located adjacent the path of the carriage, mechanism for rotating the applicator, a normally disconnected clutch controlling the operative connection between the said mechanism and the applicator, and clutch-actuating means on the carriage adapted to engage the clutch when the carriage is advanced over the applicator.

5. In a book back gluing machine, the combination with a reciprocatory carriage, of a rotary adhesive applicator element located adjacent the path of said carriage, mechanism for rotating the applicator, a normally disconnected clutch controlling the connection between the said mechanism and the applicator, and clutch-actuating and cooperative means operatively associated with the carriage and with the clutch whereby the latter is engaged during movement in one direction only of said carriage.

6. In a book back gluing machine, the combination with a reciprocatory carriage, of an adhesive applicator located adjacent the path of said carriage, and means actuated by the carriage while moving in one direction only for elevating the applicator from a normal position to bring it into contact with the books in said carriage.

7. In a book back gluing machine, the combination with a reciprocatory carriage for the books, of an adhesive applicator mounted adjacent the path of said carriage, mechanism including an oscillatory lever for shifting the applicator to bring it into contact with the books in said carriage, and cooperative means on the carriage and on said oscillatory element whereby the latter is actuated during the movement in one direction only of said carriage.

8. In a book back gluing machine, the combination with a movable carriage for the books, of a rotary adhesive applicator mounted adjacent the path of said carriage and adapted to engage the books in the latter as the carriage advances, mechanism for normally rotating the applicator, and automatic means for increasing the speed of rotation of the applicator while in contact with the said books.

9. In a book back gluing machine, the combination with a movable carriage for the books, of a rotary adhesive applicator mounted adjacent the path of the carriage and adapted to engage the books in the latter, means for normally rotating the said applicator, and means for periodically increasing the speed of rotation of the applicator in timed relation with the movement of the carriage.

10. In a book back gluing machine, the combination with a movable carriage, of a rotary adhesive applicator located adjacent the path of the carriage, mechanism for nor-

mally rotating the applicator, and means actuated by the carriage in its normal movement for increasing the speed of rotation of the said applicator.

5 11. In a book back gluing machine, the combination with a movable carriage for the books, of a rotary adhesive applicator mounted adjacent the path of the carriage, a relatively fixed brush also mounted adjacent the 10 path of the carriage and adapted with the applicator to be shifted into contact with the books moving in said carriage, and mechanism operating in synchronism with the movement of the carriage for elevating the 15 applicator and the brush.

12. In a book back gluing machine, the combination with a reciprocating carriage, of a rotary adhesive applicator mounted adjacent the path of the carriage, means for 20 normally rotating the applicator, and normally disconnected mechanism for increasing the speed of rotation of said applicator including cooperative means on the carriage 25 for actuating the accelerating mechanism during the movement in one direction only of said carriage.

13. In a book back gluing machine, the combination with a movable carriage for the books, of a rotary adhesive applicator mounted adjacent the path of said carriage, a container for adhesive in which the applicator is normally rotated, mechanism for periodically elevating the applicator to bring it into contact with books moving with said carriage, and means automatically operative with the elevation of the applicator to increase the speed of rotation of the latter.

14. In a book back gluing machine, the combination with a rotary adhesive applicator element, of a receptacle for adhesive, means for normally rotating the applicator at a comparatively low speed within the receptacle, mechanism for periodically elevating the applicator to an operative position 45 above the receptacle, and mechanism automatically operative to increase the speed of rotation of said applicator while in the elevated position.

15. In a book back gluing machine, the combination with a reciprocating carriage, of an adhesive applicator mounted adjacent the path of the carriage and adapted to contact with books moving with the latter, and mechanism for actuating the carriage 55 including automatic means for interrupting the movement thereof after each full reciprocation.

16. In a book back gluing machine, the combination with a reciprocating carriage, 60 of a gluing applicator positioned adjacent the path of the carriage and adapted to contact with the books in the carriage, mechanism for reciprocating the carriage including a rotary shaft, a source of power, and 65 mechanism including a clutch for connecting

the shaft with said source of power, manual means for engaging the clutch, and a cam member on the said shaft and adapted to disengage the clutch following each full rotation of the shaft.

70 17. In a book back gluing machine, the combination with a carriage, of an adhesive applicator located adjacent the path of the carriage and adapted to contact with the books in the carriage, mechanism for reciprocating the carriage including a rotary shaft, an arm on the shaft, a pinion journaled on the arm, and a relatively fixed gear concentric with the shaft and meshing with said pinion, a second arm pivotally secured 80 at the end of the first-mentioned arm, a gear fixed to said second arm and also meshing with said pinion, a rod pivotally secured to the outer end of said second arm and connecting the arm to the carriage, and means 85 for rotating said shaft.

18. In a book back gluing machine, the combination with a frame having a horizontal platform at one end, of a carriage adapted to reciprocate in the frame and having a pair of vertical walls intersecting at right angles and forming an open bottom pocket directly overlying the said platform when the carriage is at that end of the frame, mechanism for reciprocating the carriage, and an adhesive applicator located adjacent the path of said carriage and adapted to contact with the backs of books held against said vertical walls.

90 19. In a book back gluing machine, the combination with a carriage having a pocket 100 formed by a pair of intersecting vertical walls adapted to receive books, said walls being angularly arranged with respect to the direction of movement of said carriage, an adhesive applicator located adjacent the path 105 of movement of said carriage and adapted to contact with the exposed backs of the books held in said carriage pocket, and means for reciprocating the carriage over the said applicator.

110 20. In a book back gluing machine, the combination with a frame having a platform at one end, of a carriage adapted to reciprocate in the frame and at one end of the frame occupying a position over the platform, said carriage having intersecting vertical walls forming abutments for books supported by the said platform and against which the books are clamped as the carriage advances, mechanism for reciprocating the carriage in 120 the frame, and an adhesive applicator located adjacent the path of the carriage and adapted to contact with the backs of the books clamped as described in said frame.

115 21. In a book back gluing machine, the combination with a frame having at one end a platform, of a carriage adapted to reciprocate in the frame and at one end of the frame occupying a position overlying the platform, a pair of intersecting vertical walls in said 130

carriage with their lower edges lying substantially in the plane of said platform whereby books supported with their backs on the platform and one side and edge against the respective walls have their backs substantially on a level with the lower edge of said walls, an adhesive applicator located adjacent the path of the carriage and adapted to contact with the backs of the said books clamped against the said vertical walls of the carriage, and mechanism for moving the carriage over the applicator.

22. In a book back gluing machine, the combination of a movable carriage in which the books may be clamped with the backs exposed, an adhesive applicator extending transversely of the path of the carriage and adapted to contact with the backs of the books as the carriage is advanced, and means for supporting the books in the carriage so that all the back edges thereof are angularly arranged with respect to said applicator.

23. In a book back gluing machine, the combination of a movable carriage in which the books may be clamped with the backs exposed, and an adhesive applicator extending

transversely of the path of the carriage and at an angle with respect to all the back edges of the books clamped in said carriage, said applicator being adapted to contact with the backs of the books as the carriage is advanced.

24. In a book back gluing machine, the combination with a frame having at one end a platform, of a carriage adapted to reciprocate in the frame and at one end of the frame occupying a position overlying the platform, a pair of intersecting vertical walls in said carriage against which the books may be clamped with their backs exposed at the under side of the carriage, said platform constituting a support and gage for positioning the books with respect to the said walls, an adhesive applicator located adjacent the path of the carriage and adapted to contact with the backs of the books clamped against the walls of the carriage, means for advancing the carriage over the applicator, and flexible aprons at the lower edges of said vertical walls whose lower edges are substantially in the plane of said book backs.

JOHN J. PLEGER.
